G. L. WILLIAMSON

CLEANSING AND PAINT REMOVING DEVICE

Filed March 24, 1924

Inventor
G. L. WILLIAMSON

By *Clark Sweet - Atty*

UNITED STATES PATENT OFFICE.

GEORGE L. WILLIAMSON, OF CHICAGO, ILLINOIS.

CLEANSING AND PAINT-REMOVING DEVICE.

Application filed March 24, 1924. Serial No. 701,580.

To all whom it may concern:

Be it known that I, GEORGE L. WILLIAMSON, a citizen of the United States of America, and resident of Chicago, Cook County, Illinois, have invented a new and useful Cleansing and Paint-Removing Device, of which the following is a specification.

The object of this invention is to provide an improved device constructed and arranged for the application of a stream of heated water, and with it a chemical solution, to an object for the removing of grease, paint or other substances therefrom.

A further object of this invention is to provide improved means for applying a jet of hot water under pressure to an object, said jet mingling and carrying with it an injected stream or streams of chemical solution to be applied to the object for the removal of grease, paint or the like therefrom.

A further object of this invention is to provide an improved construction for a nozzle adapted for the application of hot water and one or more chemicals under pressure, said nozzle having connections for receiving the various liquids from separate sources and uniting them in a common stream discharged from the nozzle.

My invention consists in the construction, arrangement and combination of elements hereinafter set forth, pointed out in my claims and illustrated by the accompanying drawing, in which—

Figure 1 is an elevation illustrating the complete assembly for the application of grease and paint removing substances according to my invention. Figure 2 is an end view of the nozzle, on an enlarged scale. Figure 3 is a longitudinal section of the nozzle, showing the feed pipes attached thereto.

In the construction and arrangement of the device as shown the numeral 10 designates generally a heater shown conventionally, which may be of any desired form, having a gas service pipe 11 for supplying fuel to a burner (not shown), and water, under city main pressure preferably, is supplied to the heater, and heated therein, through a pipe 12. Heated water is conveyed from the heater by a pipe 13, with which is associated a thermometer 13'. Chemical tanks 14, 15, in this instance two in number, are arranged in elevated position, as by mounting them on a shelf 16 or other suitable support. Water

may be introduced to the tank 14 by means of a pipe 17 connected with the service pipe 12 and controlled by a cut off valve 18; and to the tank 15 by means of a pipe 19 connected with the pipe 17 and controlled by a cut off valve 20. Chemicals may be introduced to the tanks 14, 15 by pouring them therein or in any other suitable manner, to form the desired solutions with the water introduced through the pipes, and the valves 18 and 20 are closed except at such times as water is being admitted to the tanks.

A nozzle 21 is provided, having a longitudinal bore formed on several different diameters as hereinafter explained, extending from end to end and having lateral connections for introduction of various liquids. The rear end of the bore of the nozzle 21 normally is closed by a screw plug 22 which may be removed at times for the purpose of cleaning the nozzle and removing deposits from its bore or lateral connections. The nozzle 21 proper is a unitary structure, not assembled of separate parts and the bore thereof has a common wall. The rear portion of the bore of the nozzle 21 is of relatively large diameter and is designated by the numeral 23 and with it communicates a lateral passage 24 opening to the side of the nozzle and adapted to receive threaded connection of a pipe 25 with which is connected a valve 26. To the pipe 25 is connected a flexible member such as a hose 27, attached at its opposite end to a short section of rigid pipe 28 connected with the pipe 13 at the top of the heater, by means of which water, heated to the desired temperature, and under pressure of the city mains, is supplied to the nozzle.

At its inner end the passage 23 communicates with a restricted bore 29, of relatively small diameter, which in turn communicates with a passage 30, of larger diameter but yet less diameter than the passage 23. Communicating with the passage 30 is a lateral passage 31 opening to one wall of the nozzle and receiving communication of a pipe 32, equipped with a controlling valve 33. Attached to the pipe 32 is a flexible member such as a hose 34, which communicates in turn with a short section of rigid pipe 35 having communication through a T 36 with the pipe 17 leading to the first chemical tank 14. The T 36 is between the valve 18 and the tank 14, and between said T and the tank 110

is a valve 37 by means of which flow of chemical from the tank may be controlled or cut off entirely.

At its inner end the passage 30 communicates with a passage 38 of larger diameter, preferably of approximately the same diameter as the base passage 23, which passage 38 opens to the forward end of the nozzle. Communicating with the passage 38 is a lateral passage 39 opening to one wall of the nozzle and receiving communication of a pipe 40 threaded therein, equipped with a controlling valve 41. Attached to the pipe 40 is a flexible member such as a hose 42, which communicates in turn with a pipe 43 having communication through a T 44 with the pipe 19 leading to the second chemical tank 15. The T 44 is between the valve 20 and the tank 15, and between said T and the hose 42 is a valve 45 by means of which flow of chemical solution from the tank may be controlled or cut off entirely.

The several passages 23, 29, 30 and 38 are in alignment longitudinally of the nozzle 21 and constitute the bore previously referred to. The passages 24, 31 and 39 extend laterally from the bore in the same direction so that the pipes 25, 32 and 40 are arranged in spaced parallel relation and constitute a means by which the nozzle may be held and manipulated with reference to a work object, the flexible connections 27, 34 and 42 making it possible to move the nozzle about and also turn it on a transverse axis to direct the stream to the desired location. The passages 31 are inclined in the direction of the flow of liquid through the bore of the nozzle.

In practical use water is introduced to the tanks 14, 15 by opening the valves 18, 37 and 20, the controlling valves 26, 33 and 41 at the nozzle being closed. The desired chemicals are placed in the tanks to make the solutions therein. As soon as the tanks are filled the valves 18 and 20 are closed, and remain closed during use of the device. The valves 37 and 45 are opened to permit chemical solution to flow by gravity from the tanks to the pipes 35, 43 and hose 34, 42, and water under pressure also is admitted to the pipe 28 and hose 27 from the heater 10. Thereafter the nozzle is manipulated to direct a stream from the opening of the passage 38, the valves 26, 33 and 41, which are adjacent the nozzle and thus within reach of the operator, being opened to the desired extent to admit the requisite amount of liquid from each of the hose connections and its communicating members. The heated water, under pressure, passes through the lateral passage 24 and enlarged passage 23 to the restricted passage or port 29, by which it is restricted, and the water emerges in a solid stream of approximately the same diameter as said port 29, through the passages 30 and

38 from the nozzle. At the same time streams of chemical fluid enter the nozzle, from either or both of the tanks, through the lateral passages 31 and 39 and are picked up by the jet of hot water in the passages 30 and 38 and mingled with and carried along by said stream or jet of water and with it applied to the work object. The passage of the restricted jet of water through the passages 30 and 38 creates a partial vacuum in said chambers, which causes the fluids from lateral passages 31 and 39 to be carried along with it. The controlling valves 26, 33 and 41 are manipulated to control the several streams of fluid to supply the desired amount at any given time.

The chemical employed in the tank 14 is one which is a solvent of mineral and vegetable oils, effective with an application of water heated to approximately 180 degrees Fahrenheit; and the chemical usually employed in the tank 15 is a neutralizing agent which nullifies the effect of the first chemical after a certain length of time subsequent to application, so there can be no injurious effects to the work object. After application of a sufficient amount of water and chemicals, the valves 33 and 41 may be entirely closed and water alone applied to the surface to wash off any residue. The device is used for removing paint or accumulations of oil and grease from surfaces such as automobile bodies, engines and so forth, and provides an effective and rapid means for doing this.

I claim as my invention—

1. A cleansing and paint-removing apparatus, comprising a heater, a tank separate from the heater adapted to contain cleansing liquid, another tank separate from the heater and first tank adapted to contain a liquid neutralizing agent, a water-supply system communicating with said heater and tanks, a valve in said system controlling the supply of water to said tanks, a valve-controlled conduit leading from said heater, a valve in said supply system between the inlets therefrom to the respective tanks, valve-controlled conduits leading from the supply system between the first valve and the inlets to the respective tanks, valves controlling the connections between said conduits and the supply system and tanks, and a nozzle common to and communicating with all of said conduits, whereby separate liquids supplied by the tanks may be discharged by and with a jet of water from said heater, the ratio of quantities of said liquids and the heated water being controlled by the valves in the respective conduits.

2. A cleansing and paint-removing apparatus, comprising a heater, gravity-delivering tanks adapted to contain cleansing liquid and a liquid neutralizing-agent re-

spectively, a water supply system common to said heater and tanks and constant as to the heater, means for suspending the supply of water to the tanks whereby portions of said supply system are transformed into gravity-discharging systems for said tanks respectively, separate discharge conduits leading from said heater and discharge-system portions of the supply system, a nozzle common to said conduits, and valves in said conduits whereby the ratio of quantities of water, cleansing liquid and neutralizing liquid may be controlled.

3. In a cleansing and paint-removing apparatus, the combination with separate sources of supply of heated water, cleansing liquid and neutralizing liquid, of a nozzle of unitary structure having a single uninterrupted longitudinal bore having a common wall and composed of a series of end-wise-connecting passages and ports arranged in sequence and comprising a relatively large passage at its initial end adapted to receive heated water, a restricted port communicating with said passage adapted to increase the velocity of water passing through it, a passage larger than and communicating with said restricted port and adapted to receive cleansing liquid, and a still larger terminal passage communicating with the second passage and adapted to receive neutralizing liquid, means for introducing heated water under pressure to the initial passage, means inclined in the direction of the travel of the water through the bore for introducing cleansing liquid to said second passage to mingle with the water after its passage through the restricted port, and means inclined in the direction of the travel of the cleansing liquid through the bore for introducing neutralizing liquid to said terminal passage to mingle with the

water and cleansing liquid before their joint discharge from the nozzle, said introducing means being separately valve-controlled. 45

4. In a cleansing and paint-removing apparatus, the combination with separate sources of supply of heated water, cleansing liquid and neutralizing liquid, of a nozzle of unitary structure having a single uninterrupted longitudinal bore having a common wall composed of a series of endwise-connecting passages and ports arranged in sequence and comprising a relatively large passage at its initial end adapted to receive heated water, a restricted port communicating with said passage adapted to increase the velocity of water passing through it, a passage larger than and communicating with said restricted port and adapted to receive cleansing liquid, and a still larger terminal passage communicating with the second passage and adapted to receive neutralizing liquid, means for introducing heated water under pressure to the initial passage, means for introducing cleansing liquid by gravity to said second passage to mingle with the water after its passage through said restricted port, means for introducing neutralizing liquid by gravity to said terminal passage to mingle with the water and cleansing liquid before their joint discharge from the nozzle, the several introducing means opening through said common wall in spaced relation, and separate flexible connections between said introducing means and said sources of supply, said introducing means being separately valve-controlled, the water pressure being superior to the combined gravity pressures. 75

Signed at Chicago, in the county of Cook and State of Illinois, this 17th day of December, 1923.
